UNITED STATES PATENT OFFICE.

JEROME J. SOUTH, OF NASHVILLE, TENNESSEE.

CONVERTIBLE CHAIR.

1,345,513.

Specification of Letters Patent.

Patented July 6, 1920.

Application filed March 30, 1917. Serial No. 158,662.

To all whom it may concern:

Be it known that I, JEROME J. SOUTH, a citizen of the United States, residing at Nashville, in the county of Davidson and State of Tennessee, have invented a new and useful Convertible Chair, of which the following is a specification.

This invention has reference to convertible chairs, and its object is to provide a chair structure which may be changed into a table structure without unbalancing the chair in either position.

In accordance with the invention there is a stool portion provided with a seat which may or may not be permanently fast to the stool portion, and such stool portion has arm rests for the arms of the user while supported by the seat. There is also provided a table top hinged or pivoted below the arm rests of the stool, so that it may be moved and held in either the chair-back position or in the table position, in which latter position the chair back is approximately level, as is necessary for table use.

The chair-back part of the convertible chair is hinged to rails forming parts of the arms of the stool portion, and located between the arm rests and seat, in such manner as to be readily detached when desirable for shipping or storage or other purposes, but will not become accidentally detached in the ordinary use of the convertible chair in either the chair position or the table position. This permits the chair to be moved about or lifted without the parts becoming separated. The axis of the hinge connection is so located that in either position of the chair back the chair remains balanced, that is, the chair back when in the table-top position is midway of the stool part, and when in the chair-back position is so low and so close to the stool portion, although at a convenient inclination, that there is no danger of the chair tipping over backwardly even if the user desired to recline to a greater extent than the natural incline of the chair back.

In addition to a hinge structure peculiar to the convertible chair and acting as a stop and support for the chair back, there is also an automatic lock preventing unintentional movement of the chair back from the table position toward the chair back position.

The invention will be best understood from a consideration of the following detailed description, taken in connection with

the accompanying drawings forming part of this specification, with the further understanding that while the drawings show a practical form of the invention, the latter is not confined to any strict conformity with the showing of the drawings, but may be changed and modified so long as such changes and modifications come within the scope of the appended claims.

65 In the drawings:

Figure 1 is a front perspective view of the convertible chair in the chair position.

Fig. 2 is a rear perspective view of the chair of Fig. 1 with the chair back in the 70 table-top position.

Fig. 3 is a perspective view of the chair of Fig. 1 with the chair back and seat removed from their normal positions to better show some features of the chair.

75 Fig. 4 is a side elevation of a portion of the chair in the chair position.

Fig. 5 is a similar view with the chair back in the table top position.

Fig. 6 is a detail section through one side 80 of the chair and a portion of the chair seat, with the latter reversed from the showing of Fig. 1.

Fig. 7 is a perspective view of the seat part of the stool of the chair with the upper 85 portions of the legs in section, and showing a somewhat different arrangement of seat from the showing of Fig. 1.

Fig. 8 is a view similar to Fig. 7 but showing the stool arranged for a movable cushion 90 seat.

Fig. 9 is a view similar to Fig. 8 but with the cushion omitted.

Fig. 10 is a section on the line 10—10 of 95 Fig. 5.

Fig. 11 is a section on the line 11—11 of Fig. 5.

Fig. 12 is a detail section on the line 12—12 of Fig. 5, with the chair leg shown in elevation and the leg-connecting rail in sec- 100 tion.

Fig. 13 is a face view of that member of the hinge carried by a rail of the stool.

Fig. 14 is a face view of that member of the hinge carried by the chair back. 105

Fig. 15 is a perspective view of the supporting plate for a stop member carried by the chair stool.

Fig. 16 is a perspective view of the stop member associated with the supporting 110 plate of Fig. 15.

Figs. 17, 18 and 19 are sectional views of

the hinge or pivot structure showing different operative positions of the movable member with respect to the fixed member thereof.

Referring to the drawings there is shown 5 a convertible chair comprising a stool A and a back B, which latter when moved into appropriate position serves as a table top.

The stool A is shown as composed of four 10 leg members 1 with connecting rails 2 constituting a box frame, into and out of which is movable a drawer 3, having a face member 4 matching the finish of the box member, so that when the drawer is pushed in 15 it is effectively hidden and may be used for storage purposes.

The legs 1 rise considerably above the 20 box member 2, and these legs are connected at their tops by arm rests 5 at a convenient height for the occupant of the chair. Below the arm rests and above the box 2 the legs are connected by rails 6 not only 25 stiffening the parts they connect, but serving another purpose which will presently appear.

There is also provided a chair bottom 7 which may be made of a single piece of 30 wood of suitable size to fit into the box frame made up of the rails 2. Applied to the edges of the block or board 7 are strips 35 8 providing ledges to support the chair seat upon the upper edges of the rails 2. These strips are relatively narrow as compared with the thickness of the board 7 constituting the body of the chair seat, so that the 40 chair seat may be reversed and in either position project somewhat above the top of the rails 2. One face of the board 7 may be plain, while the other face has fast there- 45 to a covering 9 inclosing some more or less elastic material constituting a cushion for the face of the board 7 carrying the covering 9.

In this manner the chair seat may be so 50 located in the box made up of the rails 2 that when the device is used as a chair the seat is of a cushion nature, but when the device is used as a table the plain portion of the board 7 may be uppermost and con- 55 stitute a shelf. In Fig. 1 the seat 7 is shown with the cushion side up and in Fig. 2 with the plain side up.

The back B comprises a flat member 10 consisting either of a single board of suitable 60 dimensions or a built-up board of like dimensions. Usually such structure is a built-up structure to avoid warping.

The board 10 is provided on one face with a cushion 11 to constitute a rest for the 65 back of the user when the member B is in the chair-back position. The other face of the board 10 is plain so as to be utilized as a table top when in such position.

Secured to the member B on the cushion 70 side and near opposite edges are arms or

brackets 12, these arms each being of bowed or U shape with the free ends of the legs of the U made fast to the cushion side of the board 10 and the yokes of the U remote therefrom. The arms 12 are spread apart 70 sufficiently to embrace the arms 5 of the stool part of the chair and be located on the outsides of these arms, in close relation thereto, but preferably not in actual contact therewith, so as to avoid marring of the 75 parts by rubbing together.

The yoke portion of each arm 12 is connected to a respective rail 6 of the stool part of the chair by hinges or pivot structures which may be of peculiar construction and 80 which are best shown in Figs. 10, 11, 13 and 14. Each hinge or pivot structure comprises two members, one consisting of a plate 13 with a boss 14 projecting therefrom and provided with an axially extended headed lug 15 with the head of the lug spaced from the boss. The other member of the 85 hinge or pivot structure comprises a plate 16 with a recess 17 entering one side thereof and bordered by an overhang flange 18 ar- 90 ranged to receive the lug 15 between the head thereof and the boss 14, so that when the two parts of the hinge or pivot structure are joined, the part or member provided with the plate 16 will turn on the lug 15 95 as a pivot, and yet, because of the head of the lug and the overhang flange 18, the two members of the hinge remain firmly secured together except when purposely disconnected by moving the recessed member of the 100 hinge away from the lug member of the hinge.

That member of the hinge carrying the boss 14 is also provided with a projection or stop finger 19 on one side of the boss 14, 105 and the recessed member of the hinge has a stop tooth 20 at one end of the overhang flange and outstanding therefrom so that when one member of the hinge is turned on the other member the tooth 20 engages the 110 projection 19 and thereby prevents a turning of the movable member of the hinge beyond a certain position.

The relation of the two parts of the hinge or pivot structure for the board 10, when 115 the board is in the chair-back position, is shown in Fig. 17 where the projection 19 and the tooth 20 are in engagement, thereby preventing the hinge members from becoming separated when lifting the chair by the 120 brackets, or when converting it from chair to table-top position or vice versa. The plate 13 of each hinge structure is made fast to the outer face of a corresponding rail 6 and the plate 16 of each hinge structure is made fast to the inner face of a corresponding arm 12.

The relation of the two parts of the two members of each hinge structure, when the board 10 is in the table-top position indi- 130

cated in Figs. 2 and 5, is shown in Fig. 18. In either one of these positions the two hinge members are locked together against the possibility of disconnection. If the 5 arms 12 be grasped when the board 10 is in the chair back position the projections 19 carry the stool portion of the chair and the chair may therefore be carried from place to place without any possibility of 10 the back and stool parts of the chair becoming disassembled. When the board 10 is in the table-top position, the lug 15 and the projection 19 lock the flange 18 between them without any possibility of the table-top 15 lifting away from the stool portion or the stool dropping when the device is lifted by the table top or is moved from place to place. In order to disconnect the board 10 from the stool portion of the chair it is necessary 20 to turn the board from the chair-back position toward the table-top position and at the same time lift it bodily, and when at a point about midway between the chair-back and table-top positions the flange 18 may 25 be turned about the projection 19 as a pivot until the flange 18 is pulled away from the lug 15, which can then escape through the mouth of the recess 17 and the tooth 20 can then escape in the space between the lug 15 and projection 19. The position of the 30 parts, while this operation is taking place and just before the board 10 and hinge members attached to the stool part of the chair separate, is shown in Fig. 19. The board 10 may be replaced onto the stool 35 and the hinge members reassociated by a reverse of the movement resulting in the disconnection of the board 10 from the stool A.

40 The arms 12 are secured to the board or table top or back member 10 intermediate of the ends, so that the mid-line of the arm is midway of the length of the board 10. The hinge member provided with the plate 16 is, however, made fast to the respective arm 12 to one side of such mid line of the arm and nearer to the end of the chair back constituting the lower end thereof in the chair back position than to the upper end 45 thereof, and the slot or recess 17 is so situated that its mouth opens in a downward direction when the board 10 is in the chair-back position. The hinge member carried by the plate 13 is secured to the corresponding rail 6 nearer to what constitutes the 50 back of the chair stool than to the front thereof, but is also nearer the mid-line of the stool than to the back thereof and the projection 19 is directed toward the front 55 of the stool. When the two hinge members of each pair are connected together and the board 10 is moved to the chair back position, the tooth 20 engages the stop member 19 and the chair back is then in a moderately 60 inclined position supported in the main by

the hinge members with their engaged teeth 20 and stop members 19, while actual contact of the chair back with the rear legs of the stool is prevented by buffers 21 on the inner face of the board 10 near what constitutes its lower end in the chair back position. These buffers may be in the form of 70 rubber buttons customarily used for the purpose.

By locating one member of each hinge or 75 pivot structure to the rear side of the mid line of the arms 12, but relatively close to such mid line, and by locating the other member of each hinge or pivot structure between the mid line of a rail 6 and the 80 corresponding rear-leg of the chair stool, but also closer to the mid line than to the rear leg, the board 10 constituting either the chair back or the table top is centered from front to rear of the chair when used 85 as a table top, and is given a proper inclination and a low center of gravity when used as a chair back to avoid overbalancing of the chair, and further permitting the user to recline to a greater extent than the natural incline of the chair back, if desired, 90 without the chair being rendered top heavy and liable to easily fall over backward.

Secured to the inner face of each arm 12 95 near what constitutes the top of the board 10 in the chair back position, or the front end of the board in the table top position, is a block 22 so situated as to override the front end of the corresponding arm 5 close to the corresponding front leg 1 of the stool 100 part of the convertible chair. The end of the block 22 remote from the board 10 is provided with an engaging device 23, which may be in the form of a rubber buffer like the buffers 21 already referred to. The 105 blocks 22 are of such length that the buffers 23 will engage the arms 5 and support the board 10 as a table top in a level position, the table top being further supported by the hinge connections with the rails 6 and the table top then projects equally beyond the front and rear legs of the stool part B 110 of the chair. The blocks 22 are advantageous in the use of relatively thin standard stock for the brackets or arms 12 and also 115 for the blocks 22, without the necessity of using stock of greater thickness and wasting a large portion thereof to produce shoulders corresponding to the blocks 22.

In order to hold the table top against 120 accidental displacement when in the table top position, there is provided an automatic stop device comprising a plate 24 made fast to one of the rear legs of the stool near the top thereof, but lower than the corresponding arm 5, the location being about on a level with a corresponding rail 6. Pivoted at its lower end to the plate 24 near the lower end of the latter in the installed position of the chair is an approximately seg- 130

mental stop member or drop latch 25 provided with flanges 26 about its edges, and having a peripheral portion 27 eccentric to the pivot support of the member 25. The 5 plate 24 is provided with a lug 28 projecting therefrom toward the stop member 25, so as to be engaged by the side flanges 26 as the stop member is moved about its pivot to limit the stop member in its movements, 10 said stop member upstanding from its pivot connection with the plate 24 in the installed position of the device, and tilted so as to have a constant tendency to gravitate in one direction.

15 Secured to a corresponding one of the arms 12 on the same side of the center line of the arms as the corresponding hinge member carried by the arm, but closer to the corresponding end of the table top or 20 chair back 10 than the hinge member, is another stop 29 which may be in the form of a metallic strip having a bent portion 30 offset from the inner face of the arm, so as to engage the eccentric or cam surface 27 of the stop 25.

The parts are so positioned that the stop member 25, which is mounted on a rear leg of the stool B and has its peripheral or active cam edge 27 rising to a greater height 30 than the neighboring hinge structure, will gravitate toward the front of the stool until arrested by the lug 28. In such position it is in the path of the part 30 of the stop 29 when the board 10 is moved from the chair-back position toward the table-top position. Since the stop member 25 is free to yield to the moving stop 29, it is pushed out of the way and correspondingly raised about the pivot of the stop member 25, and then on escaping from the stop 29 the pivot stop member 25 drops. That portion of the stop member 25 first engaged by the stop 29 corresponds to the shorter radius of the eccentric or cam portion 27 thereof, so that when the stop member 25 escapes and gravitates toward its first position the eccentric portion or cam face 27 ultimately engages the stop 29 and cramps thereagainst, the buffers 23 having in the meantime come in contact with the arm 5, thus arresting the table top in the level position assuming that the stool is resting upon a level support. With the buffers 23 of yielding material, such as rubber, the 55 give of the buffers is sufficient to permit the member 25 to tightly cramp against the stop member 29 on the neighboring arm 12, thereby avoiding any looseness of the board 10 in the table-top position. The 60 table top is therefore firmly secured in the level position without the necessity of manipulating any parts and of further action than that necessary to move the board or table 10 from the chair back position to the table top position. The locking is en-

tirely automatic. When it is desired to move the board 10 from the table top position to the chair back position it is merely needful to first move the stop or latch member 25 from the cramping position in opposition to its gravitating tendency. This is done without any special effort, since the eccentric relation of the clamping surface 27 causes the stop member 25 to move toward the released position with but slight effort, 75 whereupon the table top may be readily moved to the chair back position.

The location of the hinges forward of the rear legs of the stool part of the chair and to the rear of the mid point of the 80 chair, but closer to the latter than to the rear legs, contributes markedly to the stabilizing of the chair when used for chair purposes, since the center of gravity of the chair back is low due to the low position of 85 the back with relation to the chair seat, and the centralizing of the board 10 and arms 12 with respect to the stool produces a corresponding stabilizing of the chair when used for table purposes. This is considered 90 an important feature of the invention, since it has heretofore been found difficult to avoid a tendency of convertible chairs to tip over backward, especially when used for 95 chair purposes.

Instead of a reversible seat member 7, as in Figs. 1, 2 and 3, the seat support may be permanently secured to the box 2 and the cushion cover 9 may be made fast to the 100 stool part of the chair as by means of gimp 31, as indicated in Fig. 7.

The box rails 2 may be replaced by narrower rails 2^a as indicated in Figs. 8 and 9, and a cover board 7^a may be made permanently fast thereto, this cover board serving as a shelf when the chair is in the table position, and in this case a readily removable cushion 9^a may be provided, as indicated in Fig. 8.

What is claimed is:

1. A convertible chair comprising a stool part with upstanding legs having arm rests at their upper ends, and rails below the arm rests, a back portion also constituting a table top, said back portion having brackets on opposite sides fast to one face thereof, hinge connections between the brackets and the rails located nearer to one end of the rails than to the other and also to one side of the mid portion of the brackets, and stop means at a higher point than the hinge connections.

2. A convertible chair having a stool part with upstanding arms, and a chair back constructed to also serve as a table top and hinged or pivoted to the arms at a point intermediate of the distance between the mid-point of the stool part of the chair and the rear thereof, but nearer to the mid-point of the stool part, and also interme- 130

diate of the mid-point of the chair back and corresponding end of said chair back but nearer to the mid-point of the chair back, whereby, when the chair back is in the 5 table-top position, it is centered over the stool part and when it is in the chair-back position the balance of the chair is maintained.

3. A convertible chair having a stool part 10 with upstanding arms having rails below the arm-rests of the arms, and a chair back constructed to also serve as a table top, brackets fast to the chair back midway of the ends thereof, and hinge or pivot structures each connecting a bracket on the chair back and a corresponding one of the rails below the arm rests of the stool part of the chair, and each located at a point between the rear of the chair and the mid-point of 15 the stool part of the chair and of the brackets, and nearer to the mid-point of each than to the rear thereof, whereby, when the chair back is in the table-top position, it is centered over the stool part of the chair, 20 and when it is in the chair-back position it has a low center of gravity and thereby maintains the balance of the chair.

4. A convertible chair and table comprising a stool portion with upstanding arms 30 provided with arm rests, a chair back with side brackets having a greater spread than and straddling the arm rests, a block at the forward end of each bracket on the inner face thereof, an elastic buffer on 35 each block in position to engage that end of the arm rest remote from the back of the stool portion, pivot connections between the brackets and the stool portion of the chair below the arm rests, and locking means 40 between the stool portion and the chair back mounted on one of said elements and engaging the other and located on the side of the pivot connections remote from the elastic buffers, said locking means coöperating with the elastic buffers to exert a 45 wedging or cramping action to lock the chair back in the table-top position.

5. A convertible chair comprising a stool part with upright legs rising to arm heights, 50 arm rests connecting the front and rear legs on opposite sides of the stool part, a chair back constructed to form a table top and having brackets on opposite sides fast thereto and spread apart to be located outside of and in spaced relation to the arm rests, hinge members between each bracket and the corresponding stool part of the chair below the arm rests and about which the chair back is movable from chair-back to 55 table-top position or vice versa, stop members on the inner faces of the brackets at one side of the pivot points of the latter to engage the arm rests when the chair back is in the table-top position, and an automatic locking device located on the other 60

side of and higher than the hinge connections and including a drop latch for holding the chair back in the table-top position.

6. A convertible chair and table comprising a stool portion with upstanding arms 70 provided with arm rests, a chair back with side brackets having a greater spread than the arm rests and straddling the latter, the brackets each having a separate block fast to the inner face and confined to one end thereof, a yieldable buffer on each block in position to engage an arm rest when the chair back is in the table-top position, pivot or hinge connections between the brackets and the arms of the stool part of the chair, 75 and locking means for the chair back in the table-top position and located on the side of the pivot connections remote from the buffers and having an active portion located at a greater height than the pivot connections between the brackets and chair arms.

7. A convertible chair comprising a stool part and a chair back movable from a chair-back position to a table-top position, arms or brackets on the chair back with a block at 80 the front end of each bracket on the inner face thereof, an elastic buffer on each block in position to engage a portion of the stool part of the chair, pivot connections between the brackets and the stool part of the chair, 85 and coacting cramping lock means on the stool part and chair back respectively, and located on the side of the pivot connections remote from the elastic buffers and at a higher level than the pivot connections.

8. A convertible chair comprising a stool part with upstanding arms having arm rests, a chair back with side brackets straddling the arm rests, pivot connections between the brackets and the arms for permitting movements of the chair back to 90 table-top position, separate blocks fast to the inner faces of the brackets at the front ends and conforming to the configuration thereof, said blocks extending from the connections of the brackets with the chair back for a distance therefrom and in position to overhang the arm rests when the chair back is in the table-top position, and buffers on the blocks for directly engaging 95 the tops of the arm rests.

9. A convertible chair having a stool part, a back portion movable from chair-back to table-top position and vice versa, brackets on the chair back at the sides thereof, arms 100 on the stool part straddled by the brackets, hinge structures connecting the brackets and arms, a drop latch on the stool part on one side of the hinge and having a limited drop movement into the path of the bracket, and an engaging stop on the corresponding bracket in position to strike the latch and lift it out of the way when the chair back is moved toward the table-top 105 position, and the latch having a normal 110

tendency to automatically drop back toward its first position and lock with the engaging stop on the bracket.

10. A convertible chair and table comprising a stool portion with upstanding arms provided with arm rests, a chair back having side brackets of a greater spread than and straddling the arm rests, pivot connections between the brackets and the stool portion of the chair below the arm rests, stops provided on the front ends of the brackets on the inner face thereof to engage the arm rests at the ends remote from the back of the stool, thereby disposing the stops on one side of the pivot connections, and locking means for the stool portion and chair back mounted on one of said elements to engage the other, said locking means being located on the other side of pivot connections from the stops and having a wedging or cramping action which is exerted at the termination of movement of the chair back to the table-top position, whereby when the chair back is in its last-named position it is held from moving on the pivot connections by said stops and said locking means.

11. A combination chair having a stool part and a chair back portion pivoted together, with the chair back movable from chair-back position to table-top position and vice versa, and a latch structure on the stool part of the chair and higher than the level of the pivot connections between the stool and chair back, for engaging the chair back part of the chair and locking it in the table-top position, said chair back having elastically yieldable buffers on the side of the pivot connections remote from the latch and movable into engagement with the stool part of the chair to cause the latch to tightly engage the chair back when in the table-top position and prevent lost motion.

12. A convertible chair comprising a stool part, a chair back, brackets fast to the chair back, and pivotal connections between the brackets and the stool for the movement of the chair back from chair-back position to table-top position and vice versa, the pivotal connection each consisting of a member with a headed stud and another member with a receptacle for the headed stud and provided with a side opening leading thereinto, the first named member being provided with a projection and the second member with a tooth coacting with the projection to prevent the hinge members from becoming separated when lifting the chair by the brackets or when converting it from chair to table position or vice versa.

13. A convertible chair comprising a stool part and a chair back with side brackets for connection with the stool part, and hinge or pivotal structures between the brackets and the stool part, each hinge structure being formed of two parts, one on

the stool part and the other on the corresponding bracket, and provided with coacting lock parts permitting the turning of the chair-back from chair-back position to table-top position and vice versa, said coacting lock parts interacting in either of said positions to prevent the separation of the two members of the hinge, whereby the chair back must be moved to an intermediate position and lifted away from the stool before the members of the hinge may be separated.

14. A convertible chair provided with a stool part and a chair back movable to a table-top position and vice versa, and connecting hinge structures between the chair back and stool part having coacting stop members constructed to engage when the chair back is in the chair back position, to prevent the hinge members from becoming separated when operating the chair back or lifting it by the brackets.

15. A convertible chair having a stool part with upstanding arms, each with a rail intermediate of the height of the arms, and a chair back constructed to also serve as a table top and hinged or pivoted to the rails of the arms at a point intermediate of the distance between the mid-point of the stool part and the rear thereof but nearer to the mid-point of the stool part, and also intermediate of the mid-point of the chair back and corresponding end of said chair back but nearer to the mid-point of the chair back, whereby, when the chair back is in the table-top position it is centered over the stool part and when it is in the chair-back position the balance of the chair is maintained.

16. A convertible chair comprising a stool part with upright legs rising to arm heights, arm rests connecting the front and rear legs on opposite sides of the stool part, rails connecting the legs below the arm rests, a chair back constructed to form a table top and having brackets on opposite sides fast thereto and spread apart to be located outside of and in spaced relation to the arm rests, means for pivotally connecting each bracket to a corresponding rail and about which pivotal connection the chair back is movable from chair-back to table-top position or vice versa, stop members on the inner faces of the brackets at one side of the pivot points of the latter to engage the arm rests when the chair back is in the table-top position, and automatic means located on the other side and higher than the pivot connections for locking the chair back in the table-top position with the stop members on the brackets cramped against the arm rests by the action of said automatic means.

17. A combination chair having a stool part and a chair back portion pivoted together, with the chair back movable from

chair-back position to table-top position and vice versa, cramping means at a higher level than the pivot connections between the stool and chair back, and elastically yieldable buffers on the side of the pivot connections remote from the cramping means and movable into engagement with the stool part of the chair and yieldable to cause the chair back to tightly engage the stool part when 10 in the table-top position and thereby prevent lost motion.

18. In a convertible chair, the combination with a stool having an arm rest at the top on each side and a rail at each side below and spaced from the arm rest, a chair back having a pair of brackets spaced apart sufficiently to straddle the stool, means for 15 pivoting each bracket to the corresponding

rail with said means located at one side of the mid-point of the length of the rail and 20 of the bracket, said brackets being constructed to overhang at one end the arm rests and there provided with elastic buffers forming stops, and a cramping latch between the bracket portion of the back and 25 the stool to hold the chair back in the table-top position with the buffers in firm engagement with the arm rests.

In testimony, that I claim the foregoing as my own, I have hereto affixed my signature in the presence of two witnesses. 30
